UNITED STATES PATENT OFFICE.

FRANK W. SIGOURNEY, OF BRISTOL, CONNECTICUT.

DESIGN FOR A CIGAR-HOLDER.

SPECIFICATION forming part of Design No. 16,125, dated June 9, 1885.

Application filed April 17, 1885. Term of patent 3½ years.

To all whom it may concern:

Be it known that I, FRANK W. SIGOURNEY, residing at Bristol, in the county of Hartford and State of Connecticut, have invented and produced a new and original Design for a Holder or Case for Cigars and other Forms of Tobacco; and I do declare the following to be a full, clear, and exact description of the same, reference being had to the accompanying drawing, which forms a part of this specification.

My invention consists in a design for a holder or case for cigars and other forms of tobacco.

The accompanying drawing is a perspective view of a holder illustrating my design.

Referring to said drawing, A is a receptacle of cylindrical shape, having one end rounded and closed, and the other end open and provided with a circular cover, C.

B B are side pieces situated below and one upon each side of the receptacle A. The receptacle has its open end uppermost, and is inclined relative to the parts B B.

E E are cross rods extending from one piece B to the other.

Projections F are situated upon the outer 25 surface of the parts B and in line with the lower end of the receptacle A, in imitation of trunnions, for the support of the latter.

Having thus described my invention, what I claim, and desire to secure by Letters Patent 30 of the United States, is—

The design for a holder or case for cigars or other forms of tobacco, consisting of the receptacle A, the side pieces B, and the cover C, said parts being configured and situated relative to one another substantially as set forth.

In testimony whereof I have signed this specification in the presence of two subscribing witnesses.

FRANK W. SIGOURNEY.
